UNITED STATES PATENT OFFICE

2,112,013

WRAPPER FOR CIGARETTE PACKAGES
AND THE LIKE

John Walker Chalmers, Deptford, London, England, assignor to Molins Machine Company, Limited, Deptford, London, England

Application November 12, 1936, Serial No. 110,541

2 Claims. (Cl. 229—51)

The present invention relates to wrappers for merchandise of various kinds but particularly to wrappers designed and intended for use as envelopes for packages of tobacco.

5 Cigarette packages are now commonly covered with outer wrappers fabricated of transparent sheets of cellulosic material which is of such character as to largely prevent, or at least greatly retard, the escape of moisture from the package, which is highly desirable in the case of all tobacco products. Such wrappers are generally formed from single sheets of such material and closely applied to the package to be protected by folding and gluing operations.

10 15 material is tearable but is of such character that it may not be readily torn unless an edge thereof is accessible or positioned so as to be grasped by the fingers and subjected to what might be designated a shearing action. Hence, by reason 20 of the fact that the material is transparent, and its edges may not be readily perceived, it is as a general rule difficult to readily open the average pack of cigarettes which when sold are so enveloped.

25 Prior to this it has been suggested that an exposed margin or edge of the wrapper or envelope might advantageously be provided with a tab which may be more readily grasped between the fingers than any portion of the edge itself, 30 which tab might be pulled readily in a direction to effect prompt and easy tearing of the wrapper. Despite such suggestions, however, and the actual provision of tabs of one kind or another upon 35 wrappers of this type, the common experience of tobacco users is that very considerable difficulties are met with frequently in the opening of such packages. These difficulties in large part arise from the fact that the tabs are not readily perceptible and again by reason of the fact that 40 tobacco packages are many times not opened where the visibility is such that a tab or wrapper edge may be perceived in any event. Tabs of the type heretofore suggested or used have likewise been generally of such character as to lie flat 45 against a surface of the wrapper or package and, being extremely thin, could not be detected by the sense of feel.

It is therefore the purpose of the present invention to provide a wrapper having a tab associated therewith and which tab is of such character as to be readily detectable at all times, either by sight, where the visibility is sufficient, or by feel, where the visibility is not sufficient for sight detection. In carrying out the invention a wrapper blank is fabricated preferably, al-

though not necessarily, of a single thin blank of sheet material and the tabs are formed integrally with such blank or sheet and project from an edge of the sheet which is designed and intended to occupy an exposed position after the wrapper has been applied to the package. The tabs are furthermore embossed, stamped, or roughened in any suitable manner during the process of manufacture of the blank so that, when the blank is formed into a wrapper or envelope, the exposed tab will have an appearance which is different from the remainder of the wrapper owing to the embossing, stamping, or roughening thereof. Not only will the tabs be different in appearance from the remainder of the blank, and roughened 15 so as to be more easily held during the tearing operation, but they will also be slightly thickened by reason of the raised portions or embossing and the body of the tab will tend to stand away from the surface against which it would otherwise closely lie, thus making it possible for one seeking to open the package to more readily grasp the tab.

The invention is applicable to wrappers of various shapes and formed of various materials. By 25 way of example, however, it will be disclosed as applied to a wrapper of the general type illustrated and claimed in application Serial No. 98,763, filed August 31, 1936 in the name of Thomas Grayland Jackson.

In the form of the invention selected for disclosure by way of example, the wrapper is shown to be shaped for application to a block-shaped article, which is the shape of the usual cigarette package, but it will be appreciated that the invention is not so limited.

In the drawing:

Figure 1 is a perspective view of the wrapper as applied to such a package; and

Figure 2 is a plan view of the blank from which 40 the wrapper is formed.

The blank, which is preferably of a cellulosic derivative, relatively light in weight, thin, and substantially transparent, is of such area as to provide, when folded along the dotted lines indicated in the drawing, a number of panels, major panels 10 and 11 being adapted to fit against and cover the opposite sides of the package which are the greatest in area, and minor rectangular panels 12 and 13 to rest against and 45 cover the ends of the package. The edges of the package are covered by the margins 14 and 15 of the blank, each of these margins being folded along the dotted lines shown when the wrapper is being applied. It will be understood that the 50 55

- blank is not and need not be, prescored along the dotted lines shown and that it is only divided into panels during the folding operation. The panel 16 is last applied in the covering of the ends and sides of the package and, when finally positioned, overlaps the panel 10 to approximately the extent indicated by the dotted lines 17 in Figures 1 and 2. Projecting from the edge of the panel 16 are one or more tabs 18, being integral with panel 16.
- In the process of cutting the blanks, and successive blanks are preferably cut from a continuous web, the tabs 18 are roughened, stamped or embossed, as indicated generally at 19, in any suitable manner and by any preferred means. The effect of this operation is to thicken the tabs, alter the appearance thereof, and to so roughen them that they may be more easily held by one seeking to open the package by tearing the wrapper. As may be observed from an inspection of Figure 1, the tabs are prominently positioned and may be readily detected in their roughened or embossed condition, by anyone running his hand over that face of the package upon which the tabs are located. They are furthermore readily grasped and, when grasped, may be easily pulled and the wrapper torn. To facilitate initial tearing of the panel 16, minor cuts such as indicated at 20 may be made on each side of each of the tabs 19. By the provision of these cuts tearing is facilitated, but the cuts are not absolutely necessary because the tabs may be so firmly

grasped that a substantial pull may be exerted thereon to effect tearing, without possibility of slippage.

It is apparent that the embossed tabs may be applied to the marginal edges of wrappers other than the type of wrapper illustrated in the drawing.

Having thus described the invention, what is claimed as new and desired to be secured by Letters Patent is:

1. A wrapper for a package of tobacco or the like comprising a single sheet of material extending around and completely enclosing a package, said sheet being of smooth tearable material and having an exposed edge, and a tab 15 projecting from said exposed edge, said tab being roughened to facilitate the detection and grasping thereof for the purpose of tearing the wrapper.

2. A wrapper for a package of tobacco or the like comprising a single sheet of tearable material for completely enclosing a package, opposite end portions of said sheet overlapping and being disposed in parallel planes, the outer of said overlapping portions being smooth and having a tab integral therewith and projecting therefrom substantially in the plane of said portion, said tab being roughened to facilitate the detection and grasping thereof for the purpose of tearing the wrapper.

JOHN WALKER CHALMERS.
